CLAIM

The ornamental design for a hand-held grater, as shown and described.

DESCRIPTION

FIG. 1 is a top, front and right side perspective view of a hand-held grater showing my new design with a blade exploded above in phantom lines and the feet exploded below;

FIG. 2 is a front elevation view, the rear elevation being a mirror image thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a bottom, rear and right side perspective view thereof.

The broken lines are for illustrative purposes only and form no part of the claimed design.
